UNITED STATES PATENT OFFICE

138,241

DESIGN FOR A SWIVEL BODY ELEMENT

Fred E. Anderson, Taft, Oreg.

Application January 19, 1944, Serial No. 112,264
In Canada August 30, 1943

Term of patent 14 years

(Cl. D55—1)

To all whom it may concern:

Be it known that I, Fred E. Anderson, citizen of the United States of America, residing at the city of Taft, State of Oregon, have invented a new, original, and ornamental Design for a Swivel Body Element, of which the following is a specification, reference being had to the accompanying drawing, forming a part thereof.

Fig. 1 is a plan view of a swivel body element showing my new design;

Fig. 2 is a plan view of the opposite side of Fig. 1;

Fig. 3 is a sectional view taken on line 3—3 of Fig. 2; and

Fig. 4 is a sectional view taken on line 4—4 of Fig. 1.

I claim:

The ornamental design for a swivel body element, as shown.

FRED E. ANDERSON.
